Primary Examiner—Gary D. Watson*Assistant Examiner*—T. Chase Nelson(74) *Attorney, Agent, or Firm*—Brinks Hofer Gilson & Lione**(57) CLAIM**

We claim the ornamental design for a brad nailer, as shown and described.

DESCRIPTION

FIG. 1 is a top perspective view of a brad nailer of the present invention;

FIG. 2 is a first side view thereof;

FIG. 3 is a second side view thereof;

FIG. 4 is a top view thereof;

FIG. 5 is a bottom view thereof;

FIG. 6 is a rear view thereof; and,

FIG. 7 is a front view thereof.
